UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

DEFECTIVE-NEEDLE ALARM FOR KNITTING-MACHINES.

1,270,064.

Specification of Letters Patent. Patented June 18, 1918.

Application filed June 21, 1916. Serial No. 104,910.

To all whom it may concern:

Be it known that I, ROBERT W. SCOTT, a citizen of the United States, residing in Boston, Massachusetts, have invented certain Improvements in Defective-Needle Alarms for Knitting-Machines, of which the following is a specification.

The object of my invention is to provide a knitting machine with alarm or stopping mechanism operative on the breaking of a needle butt or like accident which will prevent the needle from being properly moved by the needle actuating cams, or otherwise interfere with the orderly operation of the machine.

In the accompanying drawing—

Figure 1 is a top view of sufficient of a knitting machine to illustrate alarm mechanism in accordance with my invention with 20 which said machine is provided;

Fig. 2 is a side elevation of part of the same;

Fig. 3 is a diagrammatic representation of the needles of the machine at the draft 25 point showing the relation thereto of the member which operates the alarm, and

Fig. 4 is a top view of the parts shown in Fig. 3.

In Fig. 1 of the drawing, 1 represents the 30 head of a circular knitting machine, 2 a needle cylinder rotatably mounted therein, and 3 a post at one side of the head upon which post is mounted an ordinary gong 4. Pivotedly mounted at 5 upon the head 1 of 35 the machine is a lever 6 having three arms 6^a, 6^b and 6^c, the arm 6^c being preferably resilient and having thereon a hammer 7 for striking the gong 4.

The lever 6 is acted upon by a spring 8 40 which tends to move said lever to such position that the end of the arm 6^a overlaps the circular plane in which the needles are disposed in the cylinder 2, as shown in Fig. 1, such overlapping end of the arm 6^a being located at the point where down draft is imparted to the needles, as shown in Fig. 3, this 45 position of the free end of the arm 6^a being determined by contact of a lug 6^d on the arm 6^b of the lever 6 with one or other of a series of thread guide operating bars α with 50 which the machine is provided.

When the needles are operating normally they will have no effect upon the overlapping end of the arm 6^a of the lever and the 55 latter will occupy the position shown by full

lines in Fig. 1, the hammer 7 being then free from contact with the gong 4.

If, however, a needle butt is broken or a needle suffers any other accident which will prevent it from being drawn down to the 60 proper point by the needle actuating cams, such projecting needle (shown at 10 in Fig. 3) will strike the overlapping end of the arm 6^a and thrust the same outwardly, the movement being continued by momentum 65 until the finger reaches the position shown by dotted lines in Fig. 1, so as to cause the hammer 7 to contact with the gong 4 and sound an alarm, such alarm being repeated on each rotation of the cylinder as long as 70 the defective condition exists.

The operations described take place while the machine is knitting round-and-round, but if to-and-fro-knitting is also to be performed the arm 6^a must be withdrawn from 75 the position shown by full lines to that shown by dotted lines in Fig. 1, because, during such to-and-fro knitting, a number of needles normally occupy an elevated position and would therefore strike the projecting 80 end of the arm 6^a on each reciprocation. For this reason some means should be employed for withdrawing the finger during reciprocating knitting and restoring it to normal position again during round-and-round knitting.

Many devices may be employed for this purpose but in the present instance I have shown the arm 6^b of the lever 6 as provided with a projecting end 6^e for contact with the 90 beveled upper end 6^f of a bar 460^a such as employed in the machine shown in my Letters Patent No. 1,152,850, dated September 7th, 1915, for controlling the devices for closing the gap in the latch ring with which 95 such machine is provided, rising and falling movements being imparted to this bar at the proper times by the cam mechanism shown in said patent.

During round-and-round knitting the bar 100 460^a occupies the lowered position shown in Fig. 2, but during to-and-fro knitting said bar occupies an elevated position, the beveled upper end of the bar at such time pushing outwardly upon the end 6^e of the arm 6^b 105 of the lever 6 and thereby withdrawing the free end of its arm 6^a out of the path of the needles.

While I have, in practice, found the simple gong and hammer to provide an effec- 110

tive alarm device, my invention is not limited thereto, as an electric or other automatic alarm set in operation by movement of the arm 6^a from the position shown by full lines to that shown by dotted lines in Fig. 1, and stopped on the reverse movement of the finger, may be employed, if desired, or other modifications within the scope of my broader claims may be adopted.

10 The device may also be operated by other means than a defective needle. It may, for instance, be applied to that type of machine in which bights of yarn between adjoining wales of stitches are engaged by transfer bits, and, after being held thereby until a number of succeeding courses have been knitted, are transferred to corresponding needles, so as to form an inturned welt on the web. In such machine, any accident 15 which causes a transfer bit to retain its bight of yarn instead of properly delivering it to the needle which should receive it, will cause said retained bight to strike and operate the arm 6^a in the same manner as 20 does a projecting needle in the machine shown in the drawing.

The arm 6^a may also be caused to operate a stop motion device instead of an alarm, hence in some of my claims I have used the 25 term "emergency device" to apply to either of such adaptations.

It will be evident that by locating the hammer and hammer arm on the opposite side of the gong from that shown in the 30 drawing, the striking of the gong by the hammer can be effected by the recoil of the spring 8 instead of by the push upon the arm 6^a of the lever 6, and in some cases this disposition of the hammer and hammer arm 35 in respect to the gong may be preferred.

I claim:

1. The combination of the needles of a knitting machine adapted for both round-and-round and to-and-fro knitting, with an 40 emergency device and a lever having one arm which overlaps the normal path of the needles during round-and-round knitting, and another arm for operating said emergency device, and means for withdrawing said lever arm from such overlapping position during to-and-fro knitting.

2. The combination of the needles of a

knitting machine with an emergency device and a lever having one arm which overlaps the normal path of the needles, and another 55 arm for operating said emergency device, an intermittently moving element of the machine, and means whereby said element is caused to act upon an arm of said lever to withdraw the overlapping portion of the 60 same away from the path of the needles at intervals.

3. The combination of the needles of a knitting machine with an emergency device and a lever having one arm which overlaps 65 the normal path of the needles, and another arm for operating said emergency device, yielding means for maintaining said lever arm in such overlapping relation, a machine element which, by contact with an arm of 70 said lever, serves to limit the movement of the same in one direction, and a movable element of the machine which acts upon said arm at intervals to move it in the opposite direction and away from the needle path. 75

4. The combination of the needles of a knitting machine with an emergency device and a lever having one arm which overlaps 80 the normal path of the needles, and another arm for operating said emergency device, 85 and an operative element of the machine movable to different positions in respect to an arm of said lever, said operative element having a beveled face for acting upon said arm to remove the overlapping arm away from the normal needle path.

5. The combination of the needles of a knitting machine with an emergency device having an actuating member consisting of a pivoted lever having two arms, one of 90 which overlaps the normal path of the needles, resilient means acting on said lever to maintain said arm in such overlapping relation, a machine element acting on the other arm of said lever to limit the extent 95 of the movement due to such resilient means, and a movable member of the machine also acting upon said second arm of the lever to withdraw the other arm of the same from the path of the needles at intervals. 100

In testimony whereof, I have signed my name to this specification.

ROBERT W. SCOTT.
